Nelson M. Howard

UNITED STATES PATENT OFFICE.

SHERMAN WILLIS, OF PORTSMOUTH, OHIO, ASSIGNOR, BY MESNE ASSIGNMENTS, TO
P. R. GLASS COMPANY, OF BOSTON, MASSACHUSETTS, A CORPORATION OF MASSA-
CHUSETTS.

FRENCH-BINDING-FOLDING MACHINE.

Application filed September 26, 1921, Serial No. 503,282. Renewed December 8, 1923.

To all whom it may concern:

Be it known that I, SHERMAN WILLIS, a citizen of the United States, residing at Portsmouth, in the county of Scioto and State of Ohio, have invented certain Improvements in French-Binding-Folding Machines, of which the following description, in connection with the accompanying drawings, is a specification, like reference characters on the drawings indicating like parts in the several figures.

This invention relates to folding machines and is herein illustrated as embodied in a machine for producing a so-called French edge.

It is customary in the manufacture of certain styles of boots and shoes to bind the edges of parts of the uppers with a strip of fabric. To this end such a strip is stitched to the edge of the vamp, quarter or other piece of sheet material which is to be bound, cement is applied to the strip, and then the free portion of the binding is drawn or folded about the attached portion and about the edge of the sheet material and pressed down upon the margin of the sheet material so that the cement may hold it firmly in place. The general object of the present invention is to provide novel and improved means for performing this and similar folding and pressing operations.

According to one feature of the invention there is provided a support for a piece of work, which consists of a piece of sheet material to which a strip of binding is attached, an upwardly extending plow or folder for bending the free portion of the binding upwardly, and a presser foot directed toward the junction of the work support and the plow. The work engaged in this manner is fed over the support and past the plow, means being provided for pressing the upwardly bent portion of the binding over upon the upper margin of the sheet material.

At the locality in which the binding is wrapped about that portion of itself which is attached to the sheet material a projection or ridge is formed; and according to another feature of the invention a groove is provided at the junction of the plow and the work support to receive this ridge.

These and other features of the invention, including certain details of construction and combinations of parts will be described as

embodied in an illustrative machine and 55 pointed out in the appended claims.

Referring to the accompanying drawings,—

Fig. 1 is a perspective of a portion of the machine in which the present invention is 60 embodied;

Fig. 2 is a perspective similar to Fig. 1 but showing in addition a piece of work in process of being operated upon;

Fig. 3 is a section through the bending 65 member or plow, the combined presser foot and creaser being shown in elevation;

Fig. 4 is a perspective of the plow and presser foot;

Fig. 5 is a perspective of a modified form 70 of the invention;

Fig. 6 is a view, partly in section and partly in elevation, of the plow and presser foot;

Fig. 7 is a cross section of a piece of work 75 before it has been operated upon, and

Fig. 8 is a cross section of the same piece after it has been operated upon, both Figs. 7 and 8 being on a somewhat exaggerated 80 scale.

Referring first to Figs. 7 and 8, there is indicated at 100 a piece of leather and at 200 a strip of binding such as fabric which is attached to the leather near one edge of the leather and the binding by stitches 300. Before the piece of work is subjected to the folding operation the under side of the binding is coated with an adhesive substance which is allowed to stand long enough to become tacky. The operator then runs his 90 finger under the leading end of the free portion of the binding so as to straighten that free portion more or less and bring it into substantially parallel relation with the plane of the sheet material or leather 100. The 95 work is then fed to the machine which draws the free portion of the binding about that portion of itself which is attached to the leather and presses it over upon the margin of the sheet material so that the finished 100 work has the appearance shown in Fig. 8.

The illustrated machine is similar in many respects to that shown in the patent to Glass No. 1,281,555. It comprises a work table 9 over which the work is fed by means of a co-operating hammer 11 and an anvil 13. The anvil 13 moves back and forth in the line of feed while the hammer has a

four-motion feed movement. In order that the leading edge of the work may be engaged and bent over the hammer carries a finger 15, which extends toward the on-coming work. Besides acting to feed the work, the hammer and anvil also act to press the upwardly bent portion of the binding strip over upon the margin of the leather. The mechanism for operating the hammer and 10 anvil is or may be substantially the same as that shown in the Glass patent to which reference is made for a detailed description.

Mounted upon the table 9 in front of the hammer, that is on the side toward the 15 operator of the machine, is a combined edge gage and plow 17. In the illustrated machine this plow is integral with a base 19 which is adjustably fastened to the table by means of a screw 21 which passes 20 through a slot in the base and is threaded into the table. This construction is merely to provide for ready removal and replacement of the plow. Referring to Fig. 3, it will be seen that a portion of this base 25 19 has a surface which registers with the upper surface of the table 9 and that consequently this particular portion of the base 19 is really a part of the work support. In that portion of the base 19 which is 30 really part of the work support there is formed a groove 23 the purpose of which is to receive the ridge or thickened portion of the work which results from wrapping the free portion of the binding about that 35 portion which is attached to the leather. The plow 17 has upstanding ears which support a pivot 25; and guided between these ears and mounted upon the pivot is the stem of a combined presser foot and creaser 27. 40 The operative end of the presser foot extends diagonally toward the groove 23 which is located at the junction of a work support and the plow. Because of its shape and mounting the presser foot engages the 45 extreme margin of the leather so as to hold the ridge in the groove. As the work is fed forward it is thus caused to move in a path which maintains it in correct relation to the plow, the upturned portion of 50 the binding being guided in the space between the presser foot and the plow. A coiled spring 29, the upper end of which receives a pin on the stem of the presser foot and the lower end of which receives a 55 pin on the plow, urges the operative end of the presser foot diagonally downward so as to act upon the work in the manner which has been described above and is clearly shown in Fig. 3. In order to permit 60 the presser foot to be raised when desired, the outer end of its stem is provided with a flattened handle 31.

In the operation of the machine, after the binding strip 200 has been wiped out, 65 either by machine or manually, or at least

its leading end wiped out the work is presented to the present machine. Referring to Figs. 2 and 3, the combined presser foot and creaser 27 engages the work in the manner shown and at the same time holds 70 the ridge at the edge of the work in the groove 23, the binding being bent upwardly by the plow. As the work is fed forward progressively, the upwardly bent binding is engaged by the hammer 11 and pressed 75 over upon the margin of the sheet material.

A modification is shown in Figs. 5 and 6. In these figures the feeding and pressing means is not shown since they are or may be the same as those described in connection with Figs. 1 to 4. In this modification the plow 117 is integral with a base 119 and is mounted in a table 109 by means of a screw 121 in the same manner that the base 19 of Fig. 1 is mounted. In this modified form the groove 123 to receive the ridge at the edge of the work is formed in the plow 117 instead of in the table. The plow is of slightly different shape than the plow shown in Fig. 1 but it acts similarly 90 to bend the free portion of the binding upwardly. The combined presser foot and creaser 127 is slightly different in shape from the one first described but its operative end, like that of the one first described, 95 engages the sheet material near its edge to hold the sheet material from rising, and also permits the upwardly bent binding to pass between it and the face of the plow. The plow 117 has upstanding ears to form 100 a guideway for the stem of the presser foot but in this case the ears carry no pivot. Instead the stem of the presser foot is pivoted at 125 to a fixed portion 37 of the machine which may be part of the overhanging arm shown in the patent to Glass which has been referred to. The stem of the presser foot is provided at its outer end with a flat handle 131; and the operative end of the presser foot is urged downwardly 105 toward the groove 123 at the junction of the work support and the plow by a coiled spring (not shown) which is wound about the pivot 125 and is fast at one end to the stem of the presser foot and at the other end to the overhanging arm 37.

For convenience the invention has been described in connection with the folding of a piece of work in which a ridge is formed by the bending of the free portion of a binding strip over that portion thereof which is attached to the leather or other sheet material. It should be understood, however, that the invention is not limited to use with the particular kind of work which has been shown and described and is applicable for example to the folding of any kind of work which has a similar ridge. Although the invention has been shown 120 in connection with a machine of the type 125 130

disclosed in the patent to Glass in which the feed members act also as binding pressing members, it should be understood that the invention is not limited in the scope 5 of its application to any particular type of folding machine.

Having thus described my invention, what I claim as new and desire to secure by Letters Patent of the United States is:

10 1. A machine for operating upon a piece of work which consists of a piece of sheet material to which a strip of binding is attached having, in combination, a stationary member having a substantially flat surface 15 for supporting the main portion of the work, a member having an upwardly extending surface for engaging the binding, there being at the junction of the two surfaces a groove so located that a portion of 20 the binding engaging member overhangs it, means for holding in the groove the ridge formed by bending the free portion of the binding over the attached portion thereof, and means for feeding the work and for 25 pressing the binding.

2. A machine for operating upon a piece of work which consists of a piece of sheet material to which a strip of binding is attached having, in combination, a work 30 support, a plow extending over the work support, there being formed at the junction of the work support and plow a groove of a size and shape to receive the ridge formed by bending the free portion of the binding 35 over the attached portion thereof, a presser for holding the ridge in the groove, and means for feeding the work and for pressing the binding.

3. A machine for operating upon a piece 40 of work which consists of a piece of sheet material to which a strip of binding is attached having in combination, a stationary table for supporting the work, a plow adapted to engage a portion of the binding 45 and impart to it an upward bend, there being a groove at the junction of the table with the plow, which extends under a portion of the plow, said groove being shaped and located to receive the ridge formed by 50 bending the free portion of the binding over the attached portion thereof, a spring-pressed presser foot constructed and arranged to exert a downward pressure in a direction oblique to the vertical upon the edge 55 of the material to hold the ridge in the groove, and means for feeding the work and for pressing the binding.

4. A machine for operating upon a piece 60 of work which consists of a piece of sheet material to which a strip of binding is attached, having in combination, a table having a work supporting face, a plow the operative face of which is at an angle to that of the work support, there being a 65 groove in the corner formed by the two

faces, the plow being formed with a guideway, a presser foot extending through the guideway and having a portion located to engage the margin of the sheet material near the edge thereof, and means for feeding the work and for pressing a portion of the binding over upon the margin of the sheet material.

5. A machine for operating upon a piece of work which consists of a piece of sheet material to which a strip of binding is attached having, in combination, a work support and a plow the adjoining surfaces of which are connected by a groove having a rounded base and of such shape that one of its walls is a continuation of the operative face of the plow, a presser for engaging the edge of the sheet material in such manner as to hold in the groove the ridge formed by bending the free portion of the binding over the attached portion thereof, and means for feeding the work and for pressing the binding.

6. A machine for operating upon a piece of work which consists of a piece of sheet material to which a strip of binding is attached, having in combination, a work support, a combined plow and edge gage rising therefrom and adapted both to guide the work and to impart an upward bend to the binding, a presser foot having a narrow end directed diagonally toward the junction of the work support and the plow and adapted to press the sheet material toward the support, and means for feeding the work and for pressing the upwardly bent margin of the binding over upon the margin of the sheet material.

7. A machine for operating upon a piece of work which consists of a piece of sheet material to which a strip of binding is attached, having in combination, a work support, a combined plow and edge gage rising therefrom and adapted both to guide the work and to impart an upward bend to the binding, a presser foot having a narrow end directed diagonally toward the junction of the work support and the plow and adapted to press the sheet material toward the support, yielding means for holding the presser foot in contact with the work, and means for feeding the work and for pressing the upwardly bent binding over upon the margin of the sheet material.

8. A machine for operating upon a piece of work which consists of a piece of sheet material to which a strip of binding is attached having, in combination, a work supporting member and a fold forming member rigid with each other, there being at the junction of their operative surfaces a groove having a rounded base one wall of said groove being a continuation of an operative face of one of the members, a presser foot having a narrow end directed diagonally to

ward the groove and adapted to hold in it the ridge formed by bending the free portion of the binding over the attached portion thereof, and means for feeding the work and 5 for pressing the fold.

9. A machine for operating upon a piece of work which comprises a piece of sheet material to which a strip of binding is attached having, in combination, a member for 10 supporting the work in a substantially horizontal position, a plow having an upwardly extending operative face, there being at the junction of the plow and member a groove adapted to receive the ridge formed by 15 bending the free portion of the binding over the attached portion thereof, a presser having a narrow operative end, a pivot upon which the presser is mounted, the shape of the presser and the location of the pivot 20 being such that when swung downwardly about its pivot the presser exerts upon the edge of the material a force oblique with respect to the vertical to hold the ridge in the groove, and a spring for causing the 25 presser to act continuously upon the work.

10. A machine for folding a piece of work having a ridge near one edge thereof having, in combination, a stationary member having

a substantially flat surface for supporting the work, a plow having an upwardly extending surface for engaging and bending upwardly the margin of the work, there being substantially at the junction of the two surfaces a groove so located that a portion of the plow overhangs it, means for holding the ridge in the groove, and means for feeding the work and for bending over and pressing the margin thereof. 30 35

11. A machine for progressively feeding and folding a piece of work having a ridge near one edge thereof having, in combination, a support for the work, a plow extending upwardly from the support in position to engage the margin of the work, there being a groove located substantially at the 40 junction of the work support and the plow to receive the ridge, a spring-pressed presser-foot constructed and arranged to exert a downward pressure upon the work in the locality of the groove to hold the ridge in 45 the groove, and means for feeding the work and for pressing downwardly the margin thereof. 50

In testimony whereof I have signed my name to this specification.

SHERMAN WILLIS.
